UNITED STATES PATENT OFFICE.

JOSEPH BATTAGLINO, OF EL PASO, TEXAS.

AUTOMATIC STOP AND ADVISER FOR LOCOMOTIVES.

1,284,987.

Specification of Letters Patent. Patented Nov. 19, 1918.

Application filed July 2, 1914. Serial No. 848,651.

To all whom it may concern:

Be it known that I, JOSEPH BATTAGLINO, a citizen of the United States, residing at El Paso, in the county of El Paso and State of Texas, have invented certain new and useful Improvements in Automatic Stops and Advisers for Locomotives, of which the following is a specification.

An object of my invention is to provide means on the locomotive connected with the throttle and with the air brake control valve in such relation that when the said means is operated these parts are actuated to cut off the motive power and to apply the brakes to bring the locomotive to a stop, and means located along the track to be brought to a relation to cause said means to become operative.

A second object is to so connect the means located along the track with a semaphore or switch that when the semaphore or switch is moved to one of its positions, the said means will be brought to a position to operate the means carried by the locomotive.

A further object is to connect the parts carried by the locomotive in such relation that when the train is to be stopped, the motive power is first cut off and then subsequent to this operation the brakes are automatically applied.

A still further object is to so arrange the parts carried by the locomotive and the means located along the track that under certain operating conditions only the means connected to actuate and cut off the motive power is operated and the train is permitted to drift under the inertia derived from the normal operation until it comes to a natural stop by a loss of momentum or until a second track means is encountered which operates to actuate the brake setting means carried by the locomotive to bring the train to a positive stop.

Another object is to construct the parts carried by the locomotive and the means located along the track in such a manner that the several parts are electrically controlled and the control is actuated by the operation of the semaphore or switch with which the mechanism of my invention is intended to work.

Yet another object of my invention is to construct and connect the parts in a manner that under certain conditions, as for instance where the signal of the semaphore is set at proceed, the only effect will be to

record on recorder tape or other recording apparatus that the signal has been passed, under other conditions, as for instance where the signal is set to indicate that the train should proceed with caution, the parts carried by the locomotive will be actuated so that the motive power will be cut off and the train permitted to drift, giving an audible alarm to the engineer, and under a third condition, exemplified by the setting of the signal to indicate that the train should be stopped, both the means for cutting off the motive power and the means to cause the brakes to be set will be operated and the train will be brought to a positive stop.

It is also an object of my invention that means shall be provided connected with each of said operating parts on the locomotive and to be operated as the locomotive passes the track means to make a permanent visible record of the setting of each of said track means, and further to construct the several operating parts on the locomotive in such a manner that when once actuated by a track means set to cause their operation, the resetting to permit the locomotive to proceed under normal conditions causes a record to be made of their operation, which last record is independent of the permanent visible record above-mentioned.

With other objects in view, which will be referred to, my invention consists in the peculiar combination and novel arrangement of parts, such as will be hereinafter more fully described in connection with the accompanying drawings and more particularly pointed out in the appended claims, and with parts of the structure illustrated in section.

In the drawings:—

Figure 1 is a schematic view in side elevation of a section of track with semaphores and track means connected in a relation to be adaptable to my invention.

Fig. 2 is a view of the disclosure in Fig. 1 with the track shown in plan and the operating parts diagrammatically indicated.

Fig. 27 is an elevation of a structure adapted for use on the controller handle of an electric locomotive or electrically propelled railway car.

Fig. 28 is a view in top plan of the mechanism disclosed in Fig. 27.

Fig. 29 is a schematic view similar to Fig. 5 with the parts carried by the locomotive

illustrated in a modified arrangement adapted to attain a slightly different result in operation.

It has been found desirable in adopting this invention to use, to connect the parts carried by the locomotive in an electric circuit independent of any electrical connection or source of electrical energy carried by the engine and so connected and arranged

that as a contact is made to pass a current through the circuit in one direction one

function is accomplished, and as the current is passed in the reverse direction through the circuit a relatively different operation

of the parts to be actuated by the electrical energy of the circuit is obtained. To accomplish this passage of the electrical current through the circuit in the one direction

or the other, the track devices 1, 2, 3, and 4 are made in the form of contacts. The batteries 5, 6, 7, and 8 are located at a suitable point along the track and line wires

9, 10, 11, and 12 are connected with these batteries and are brought to a point where

they may be connected with the wires 13 and 14 of the contact circuits which are connected with the several contacts of the track devices.

The battery 5 may be connected by wire 9 with circuit wire 13 at its negative pole and the positive pole is grounded,

battery 6 is grounded at its negative pole and wire 10 connects the positive pole thereof with the circuit wire 13, battery 7 has the negative pole thereof connected with the circuit wire 14 by the wire 11 and the positive pole is grounded, and the wire 12 may

connect the positive pole of battery 8 with the circuit wire 14, a suitable connection being provided between the negative pole of this battery and the ground. It is prefer-

able that the several contacts 1, 2, 3, and 4 be placed between the rails 15 and 16 and that the contact 1 which will be hereinafter referred to as a distant signal contact be connected with the circuit wire 14 which is

also connected to the contact 3, this latter contact being referred to hereinafter as a home signal contact. The two remaining contacts 2 and 4 will be referred to as a home signal contact and a distant signal contact, and these contacts are connected in

the circuit wire 13.

The rails 15 and 16 are grounded in the sections parallel to the contacts 1, 2, 3, and 4, and the track circuit embraces other

structure, the correlative positioning and operation of which will be set forth as the

description proceeds.

The contact members 19 and 20, Figs. 3 and 4, are supported on the pilot 26 of the locomotive by brackets 25 and hoods 21 and 22 are mounted above these contact brushes

to form protective shields therefor. The contact brush 19 is placed at such a point

on the locomotive that it will engage with

12

13

each of the distant signal contacts which are placed to be in alinement and preferably midway transversely between the rails, and the contact brush 20 is positioned to one side of the contact brush 19 in such relation that it will engage with either the home signal contacts 2 or 3 as the locomotive may be passing in the one direction or the other. A locomotive circuit wire 23 10 is connected with contact brush 19 and the circuit wire 24 is connected with the brush 20.

It is preferable that the contacts 1, 2, 3, and 4 be provided on their operating faces with a plurality of contact plates 27, mounted transversely thereof and at spaced apart points, as better shown in Figs. 3 and 4 so that the contact brushes 19 and 20 will be given a vibratory movement in passing over the contacts to cause any foreign matter which may be upon the brushes or upon the contact to be discharged therefrom to permit a direct bearing of the one against the other and a perfect connection. However, in some connections, as for instance where the contacts may have a coating of ice, snow or other foreign substance thereon which would not be readily removed by the passage of the brushes 19 and 20 there- 30 over, it may be found desirable to provide the cleaning brushes 28 and 29 mounted to be revolved directly in front of each of the contact brushes 19 and 20. The mount- 35 ing of these brushes 28 and 29 is accom- plished by providing a frame 30 pivot- ally connected with the brackets 25 and 31 to have swinging movement around this pivot. The shaft 32 on which the cleaning brushes 28 and 29 are threaded to have a 40 friction joint, is mounted on the frame 30 and the rod 33 connected with the pilot 26 extends down through openings provided in the frame 30 and have the coil springs 34 and 35 mounted therearound to bear against the upper and lower side of the free end of 45 the frame 30 and hold this frame at a position that the cleaning brushes 28 and 29 will come into the proper bearing contact against the plate of the several contact members. A 50 belt 36 connected over a pulley wheel 37 mounted on the pilot wheel axle 38 is passed over the several idlers 39 and then around the belt wheel 40 on the brush shaft 32 in such a manner that the rotary motion of the 55 axle 38 is reversed when transmitted to the shaft 32 to cause this shaft and the cleaning brushes 28 and 29 having the frictional turning connection thereon to be revolved in the opposite direction. Under ordinary condi- 60 tions, the cleaning brushes 28 and 29 in their rotary travel over the contacts will remove any foreign substance therefrom, but under circumstances where a very heavy coat of ice or a tenacious coating of any other sub- 65 stance may be deposited upon the contacts, it

may be found desirable to use one or more sets of cutting teeth 41 upon each of the brush rolls to accomplish a more vigorous cleaning action than would be attained by the use of the cleaning brushes 28 and 29 70

It will be understood that the wires 23 and 24 of the locomotive circuits are insulated from each other and from the structure on the locomotive, the wire 23 connected 75 with the contact brush 19 is extended along the locomotive structure to connect with re- sistance 23^a and electrically actuated parts in the automatic alarm box 41, from this alarm box, circuit wire 23 is carried to a recorder 80 85 or other suitable recording means adapted to furnish a permanent visible record of its operation, and from this point the circuit is lead by a wire 43 and is grounded on the mass of the engine. The locomotive cir- 90 circuit wire 24 connected with the contact brush 20 extends to and is connected with the part of the electric switch 44 from which a branch wire 45 connects with the circuit wire 23. The circuit wire 24 is extended 95 from the switch 44 to connect with the electrically actuated part of a fluid valve 46 provided to control the passage of fluid to the automatic throttle shift mechanism 47, and from this valve the wire 24 is connected 100 with the circuit wire 23 at a point in front of the automatic alarm box 41. By connect- 105 ing the parts in this manner, it will be seen that as the distant signal contact brush 19 passes over one of the distant signal contacts, current is supplied from either the negative or positive poles of one of the batteries which has its opposite pole grounded and this current will flow through the sev- 110 eral wires and connecting parts to the loco- motive circuit wire 23 from whence it passes through the automatic alarm box, the re- corder and thence through the wire 43 to the mass of the structure of the locomotive, then, as the locomotive is passing over the 115 rails of the track which are grounded, the circuit will be completed. When the contact brush 19 comes into bearing relation upon one of the distant signal contacts, the cur- 120 rent passes only through the wire 23 of the locomotive circuit and the parts connected therein; however, when the contact brush 20 carried by the locomotive in a position to en- gage with either of the home signal contacts 2 or 3 comes into bearing relation there- 125 against, the current is supplied through the wire 24 to the electric switch 44 and through the wire 24 to the fluid-valve actuating means contained at 46 and then on through the wire 24 to the circuit wire 23, thus the fluid valve 46 is operative only when the contact brush 20 passes over one of the contacts 2 or 3, but on the other hand the auto- 130 matic alarm 41 and the recorder 42 are actuated when either the contact brush 19 or

the contact brush 20 comes into bearing relation with respect to one of the contacts located along the track.

The automatic alarm box is connected 5 with the air reservoir by a pipe 48 in such relation that immediately after the electrically operated means contained within the box is actuated the fluid pressure supplied through this pipe causes the alarm to be 10 sounded. A pipe 49 connected with the same source of fluid supply as the pipe 48 and extends to the fluid valve 46 from thence a pipe 50 extends to connect with the automatic-throttle shift mechanism 47. A cable 15 51 is connected with a movable member of the throttle-shift mechanism and with the operating lever of the engineer's throttle 52 in such relation that as fluid is supplied through the pipe 50 this throttle lever is released and thrown to a position that the motive power is cut off. A fluid pipe 53 is connected with the throttle-shift mechanism 47 at a point that communication thereto is not established until the throttle lever has been 20 moved to a point to cut off the motive power and this fluid pipe 53 connects on its free end with a brake-valve handle operating cylinder 54. The engineer's brake valve 55 is mounted at any desired point on the locomotive, the brake control box being located 25 between this brake valve and the operating cylinder 54, the cable 56 being connected between the cylinder 54 and the valve control box, a connection being established to the 30 valve handle to 198 and 199, and as air is supplied to the operating cylinder 54, the brake valve handle 55^a is actuated and causes 35 this brake valve control mechanism to be operated.

40 If through some unusual condition of service, the locomotive is required to pass a home semaphore displaying "Stop" the switch 44 is operated by hand and the connection between wire 24 and 23 through wire 45 is established.

45 The above subject matter comprises a somewhat complete description of the general scheme of my invention, and the several parts will now be taken up and described in detail in the order of their connection and operation.

50 The mounting of the automatic alarm box 41 in the circuit wire 23 and the extending of the circuit wire 24 to connect with the 55 wire 23 at a point in advance of the disposition of the alarm box places this box in such relation that when the locomotive occupies a position upon the grounded portion of the rails 15 and 16 and passes over one of 60 the contacts to bring one of the contact brushes 19 or 20 into engagement therewith, the circuit is passed through the wire 23 in that part which has the alarm box 41 connected therein and the electrically connected 65 parts contained therein are energized.

The alarm box 41 comprises in the main a cylinder 57 having the magnet box 58 made integral therewith, and a support 59 is connected with the cylinder. A fluid tube 60 has a passage 61 therefrom to establish communication with the cylinder at a point low down in the cylinder and the pipe 48 from the air reservoir is connected with this tube 60. The pipe 48 is connected virtually in an arm 62 of the tube 60 and a needle valve 63 is provided in the passage from this arm or branch to the main portion of the tube. A valve 64 of the piston type, the structure of which will be more fully hereinafter described, is connected in a pipe 65 leading 70 from the fluid tube 60 and a branch pipe 66 leads from this valve 64 and is connected with a whistle 67 or other suitable alarm. The stem 68 of the valve 64 extends up through the valve casing which is connected 75 with the support 59 and to a point above the support where it is connected with the body of the lever 69 which in turn is pivotally connected by a pin 70 at one of its ends to the support 59, the connection from the fluid 80 supply pipe 48 through the fluid tube 60 to the valve 64 is so arranged that the pressure of the fluid from the air reservoir will normally exert a pressure against the piston valve within the valve casing to bring this 85 valve to an open position where the air can pass through the pipe 66 to the whistle 67. A piston 71 is mounted in the cylinder 57 and the stem 72 thereof is extended up 90 through the support 59 and is made bifurcated to receive the free end of the lever 69, a friction roll 73 being provided to reset the lever 69 after each operation. An adjusting screw 74 is carried by a bracket 75 mounted 95 on the support 59 alongside the swinging 100 path of the lever 69 and this screw limits the upward swinging movement of the lever. A coil spring 76 is received around the piston rod 72 to bear between the upper side of the piston 71 and the inner upper cylinder head 105 and to force piston 71 down when pressure is exerted under it and the valve 64 is normally closed. However, as the cylinder 57 below the piston 71 is constantly in communication 110 with the air-supply pipe 48 through the passage 61, and pressure is being exerted against the piston of the valve 64 to open this valve, it has been found desirable to provide some means of holding the lever 69 normally in its depressed position or the 115 position shown in Fig. 10.

The locomotive circuit wire 23 leads from the contact brush 19 to the binding plate 77 and the binding plate 78 has the return lead of this circuit wire connected therewith. A 120 catch 79 is pivoted at 80 on the alarm box and the arm 81 thereof has a coil spring 82 attached thereto and at its free end connected with the pin 83 carried by the bracket 75 so that this catch is by the action of the 125 130

spring swung to a position out of engagement with the lever 69. A permanent magnet 84 is connected rigidly by a bolt 85 in the magnet case 58 adjacent an opening provided through the upper side of this box at a point beneath the position which the arm 81 occupies when the catch 79 is in engagement with the lever 69. This permanent magnet 84 is of the usual U-bar type and the soft metal cores 87 and 88 are connected with each pole thereof and extended up through the opening in the case to a position that the arm 81 engages with and rests thereagainst when the catch is swung to the position shown in Fig. 9, and the catch 79 is held in its operative relation against the tension of the spring 82. The coils 89 and 90 are mounted around the cores 87 and 88 to be connected together and connected by suitable wires with the binding plates 78 and 77 in such relation that when a current is passed through the circuit wire 23 in either direction these coils are energized and through the connection of the cores 87 and 88 by the permanent magnet 84 an electromagnet is formed which magnet acts to either attract or repel the arm 81. As the current passes in the one direction through the circuit wire 23 and consequently to the coils the attracting power exerted by the magnet structure upon the arm 81 is increased, but upon a reversal of the current in its passage through the coils the polarity will be reversed and the arm will be released to be permitted to rise under the tension of the spring 82, and 69 freed of the latch 79 is elevated by the fluid pressure under 64^a and air is permitted to pass from 61 to 67 through valve 64 and connection 40 blowing the alarm 67. The efflux of air through 67 is greater than the influx in 63, therefore the pressure under piston 71 is decreased. Spring 76 will force 71 down carrying in its bifurcated rod the lever 69 in the downward movement until it is retained by 82^a. As the pressure is continually being decreased under 71 the spring 76 will overcome the resistance of the leaf spring 83^a on 82^a and force 69 down on 81 with a blow 50 strong enough to carry it against the cores 87 and 88 where it is retained by the magnetic power of 84. Contemporaneously 69 is locked by 79 stopping the flow of air in valve 64.

55 The circuit wire 23 is carried from the binding plate 78 to the recorder 42 or to some other suitable recording means which will make a permanent visible record of the passage of the brush contacts 19 and 20 over the track contacts and the operation of the parts carried by the locomotive; this recording instrument being of the standard construction and operation will not be described here in detail but it will suffice to say that the instrument may be one adapted

to record by punching a sheet or tape, marking thereon, or in fact indicating in any way in a legible permanent form the condition and direction of passage of the current through this instrument. The circuit is conducted from the instrument 42 by a wire 43 and is grounded on the mass of the engine, this connection through the structure of the engine completing the circuit as hereinbefore set forth.

75 The locomotive circuit wire 24 leading from the brush contact 20, while connected with the circuit wire 23 and therefore in a relation to cause the recording instrument 42 to be operated, is intended primarily to 80 be connected with the throttle closing and brake-valve actuating means in such relation that as the brush contact 20 passes over one of the track contacts 2 or 3, the current passing in the one direction to this wire will 85 cause the brake valve and lever to be actuated and passing in the opposite direction will permit these parts to remain in a position that the train can proceed under normal conditions, and the only effect is the recording of the contacts at the instrument 42.

My invention may be applied with equal facility to either a steam locomotive or an electrically propelled locomotive or car and the operation will be equally efficient. In 95 use on a steam impelled locomotive, the throttle 52 will be modified and changed only to the extent shown in Figs. 25 and 26, the throttle rod 91 being pivotally connected to the engineer's throttle lever 92 and the 100 spring-held dog 93 actuated by the grip lever 94 provided to engage with the teeth of the segmental rack 95 and hold the parts in their adjusted position. A draw rod 96 provided with an eye on the end thereof is 105 connected with the inner side of the grip lever 94 in such relation that when a pulling tension is exerted upon the draw rod 96 this grip lever is moved to a position to release the dog 93 from the teeth of the rack 110 95 and as the drawing tension is continued the throttle lever 92 will be swung around its pivotal connection and the steam will be cut off. The application would be very similar on an electrically propelled vehicle, 115 one adaptation of means to cut off the power being shown in Figs. 27 and 28 where the controller 97 has a drum 98 secured adjacent the controller handle 99. A pulley 100 mounted on the controller box has a cable 120 101 secured to the drum 98 passing thereover and connected with the means to transmit a drawing tension thereto to turn the drum 98 and to swing the controller handle 99 to a position that the power is cut off 125 from the driving part of the vehicle.

This means for exerting a drawing pressure on the draw rod 96 or in the adaptation of the structure to an electrically propelled vehicle, to the cable 101, may be of any type 130

although I prefer any fluid operated means as such means is both simple and positive in its action. The structure of this automatic throttle shift, as shown in detail in Figs. 16 and 17, comprises the cylinder 102 which has the piston 103 mounted therein to have its piston rod 104 extended through the rear end thereof and the pipe 50 from the fluid valve 46 connects with this cylinder 102 at a point in advance of the greatest inward stroke thereof. The slide rods 105 are mounted on either side of the cylinder 102 to have sliding movement in a line parallel with the movement of the piston, a cross yoke 106 connects these slide rods at their forward end and a similar yoke 107 is connected between the rear end of these slide rods 105 and with the piston rod 104 in such relation that as the piston is moved by the supply of fluid to the cylinder through the pipe 50 the slide rods 105 and the cross yoke 106 are carried therewith. An eye bolt 108 is received through an opening provided in the cross yoke 106 and is secured at its inner end to a slide yoke 109 which is held resiliently spaced from the cross yoke 106 by the coil springs 110 which are received around the slide rods 105 between the yokes 106 and 109. The cable 51 is connected between this eye bolt 108 and the draw rod 96 in such relation that it exerts a pulling tension upon this draw rod to operate the throttle lever as above described. A hook 111 is pivotally mounted on the forward end of the cylinder 102 to have an arm 112 extending beyond the pivot. A spring 113 is mounted behind the sliding piston 114 provided in an orifice formed in line with the arm 112 and this piston normally bears against the arm to hold the hook in the position indicated in Fig. 17 where it is above or out of the path of the yoke 109. A duct 115 is provided through the front end of the cylinder 102 to connect with the interior thereof and a sliding piston 116 is mounted in this duct in such relation that it bears against the bottom of the hook member 111 and as fluid is supplied through the interior of the cylinder through the pipe 50 this piston 116 will be moved in a direction to overcome the tension of the spring 113 bearing through the piston 114 against the arm 112 and will bring the hook down to a position that when the piston rod 104 has been sufficiently extended from the cylinder to draw the yoke 109 within the scope of the hook 111 this hook will engage with the yoke and the throttle 52 will be held in a closed position.

60 The pipes 53 connect with the cylinder 102 of the throttle shift mechanism 47 at a point adjacent the outer end and is so positioned that communication is not established thereto from the fluid-supply pipe 50 connected with the air reservoir until the piston

103 has traveled into proximity to its extreme outward thrust; thus fluid is not supplied to the brake-operating cylinder 54 until the throttle-shift mechanism 47 has operated to positively lock the throttle 52 in a closed position. The cylinder 54 has a piston 117 mounted therein and a coil spring 118 mounted around the piston rod 119 to bear between the cylinder head and the piston holds this piston normally at the inner end of the cylinder. The pipes 53 connect with the inner end of the cylinder 54 in such relation that as fluid is supplied to this pipe the piston is forced against the tension of the spring 118 to the opposite end of the cylinder to extend the piston rod 119 therefrom. The draw rod 120 slidably mounted on the cylinder 54 is connected with the piston by an arm 121 in such relation that as the piston rod is extended from the cylinder this draw rod 120 is moved endwise to exert a pulling tension upon the cable 56 which is connected therewith and at its opposite end with the link 198 on the brake valve control box. This same pulling tension upon the cable 56 causes the operative parts contained in the brake-valve control box 122 to be brought into operative relation.

As hereinbefore stated, it is essential to the successful operation of my invention that fluid be supplied to the throttle and brake operating means only when the contacts 2 and 3 are set to accomplish the passage of current through the contact brush 20 and the circuit wire 24 connected therewith in one direction, and to accomplish this end, I provide the fluid valve 46 connected between the fluid supply pipe 49 connected with the air reservoir and the fluid pipe 50 connected with the throttle-shift mechanism 47.

The fluid valve 46 comprises the valve proper 123 of the piston type and the case 124 which contains the mechanism connected to operate this valve. The valve 123 comprises a case which has a branch 125 connected with the pipe 49 from the air reservoir or other suitable source of fluid supply and a branch 126 in which the pipe 50 extending to the cylinder 102 of the automatic throttle shift is connected. A wall 127 is formed in the case at a point adjacent the branch 126 and the bore thereof extends in a direction parallel with the extent of the opening through the arm 125. The wall 127 has a plurality of openings 128 formed therethrough in such relation that the fluid is permitted to pass from the branch 125 through these openings to the branch 126 and in consequence communication is established between the pipes 49 and 50. The piston valve 129 is mounted within the valve casing and in a position to slide and work within the bore of the wall 127 so that when

5 moved to the position shown in Fig. 15, communication is cut off from the branch 125 to the branch 126 of the case; however, as the pressure of the fluid is always against the head of this piston valve, the tendency is for the valve to be raised to a position above the opening 128 to establish communication from the pipe 49 to the pipe 50. The stem 130 of the valve 129 is extended up 10 through the valve casing and into the box or case 124 which contains the operating mechanism. To release the throttle 52 from the closed position to which it has been moved by the supply of air through the pipe 50 to the cylinder 102 which tends to exert a pressure against the piston 103 and a drawing tension upon the cable 51, it is necessary that the pressure in this cylinder be released to permit the return movement 15 of the piston and also to permit the spring 113 to move the hook 111 to the position indicated in Fig. 17 where it is out of locking engagement with the cross yoke 109, and to accomplish this escape of the fluid pressure from the cylinder 102, I provide the escape ports or ducts 131^a through the upper portion of the valve case 123 in such relation that when the piston valve 129 is in its closed position, or in the relation 20 closed in Fig. 15, communication is established back through the pipe 50 from the cylinder 102, through the passages 128 in the wall 127 to these outlets or escape ports 131^a and the air pressure in the cylinder exerting a moving force against the piston 103 and 116 is relieved.

The valve case 123 is connected with the box 124 and the valve stem 130, as stated, extends up into this box.

25 A hand operated lever 131 is pivoted at its one end to the side of the box 124 and the valve stem has a pivotal connection therewith at 132. That end of the box toward which the hand lever 131 extends has a door 133 connected therewith by hinges 134 and a spring 135 engages with a draw rod 136 connected with the door to hold this door normally in a closed position. A catch 137 is mounted on the door 133 and a spring latch 138 is carried by the hand operated lever 131 in position to engage with this catch and hold the door in a closed position when the hand lever occupies the additional means of securing the door in a closed position the latch 139 is provided to be manually actuated. A swinging bar 140 is pivotally connected at 141 to the bottom of the box 124 to have its movement in a horizontal direction and to swing to a position to engage in the notch 142 formed in the side of the valve stem 130, which notch it brought to the proper relation when the hand operating lever 131 is depressed to bring the piston valve 129 in its closed position.

30 A frame 143 connected with the bottom of the box over the swinging bar 140 has a friction roll 144 mounted therein to bear against the top of this bar and prevent distorted movement due to the pressure of the fluid from the air-supply pipe 49 against the piston valve 129 and consequently against the valve stem 130 and an adjusting screw 145 is provided in the frame to limit the extent to which the bar 140 may be swung in a direction opposed to that at which it engages with the valve stem 130, a spring 146 the bearing tension of which is adjusted by the tension screw 146^a being mounted to bear against a push rod 146^a 35 which bears upon the bar to exert a pressure to move the bar from its position of engagement within the notch 142.

A permanent magnet 147 similar to that embraced in the electrically actuated mechanism of the automatic alarm box 141 is connected by a suitable securing means 148 in horizontal alignment with the swinging path of the bar 140 and in proximity to the outer end thereof. This permanent magnet 40 has the soft metal cores 149 and 150 connected with the opposite poles thereof to extend into proximity to and to attract the free swinging end of the bar 140. The cores 149 and 150 have the electro-magnetic coils 45 151 and 152 mounted therearound and these coils are connected together and with the binding plates 153 and 154 suitably insulated from each other and from the structure of the box. The locomotive circuit wire 50 149 establishes an electric connection between the switch 44 and the binding plate 154, the circuit then passing through the coils 151 and 152 to the binding plate 153 from which 55 the circuit wire 24 is extended to connect 105 with the circuit wire 23 at a point in advance of the connection of the automatic alarm box 41.

Under ordinary working conditions, or when the train is passing along the track between the track contacts, the permanent magnet 147 will exert sufficient attractive force against the free end of the pivotally mounted bar 140 to hold this bar in engagement with the notch 142 of the valve stem 110 130 and retain the valve in its closed position. This pressure or force of attraction exerted by the magnet is sufficient to overcome the tension of the spring 146 and as the current is passed through the circuit wire 115 24 into one direction by the engagement of the contact brush 20 with one of the contacts 2 or 3, the passage of the current through the coils 151 and 152 in a clockwise direction will only tend to exert a greater attracting 120 force upon the bar 140 and this bar will still be retained in engagement with the notch 142; but, if the contacts engaged by the brush 20 be of an opposite polarity, the current 125 is sent through the coils in a counter- 130.

clockwise direction and a counterforce is exerted by the magnetism of the cores 149 and 150 against the attracting cores of the permanent magnet 147 which releases the bar 140 and permits it to be swung by the tension of the spring 146 from its position of engagement in the notch 142. With the release of the bar 140 from its engagement with the valve stem 130, the pressure of the air from the pipe 149 against the valve 129 raises this valve to a position where communication is established through the opening 128 with the pipe 50 to the forward end of the cylinder 102 of the throttle-shifting mechanism 47. This movement of the valve 129 causes the valve stem 130 to be moved in an upward direction and in consequence the hand-operated lever 131 is swung around its pivot and the spring latch 138 is disengaged from the catch 137 carried by the door. Thus the door 133 may be opened against the tension of the spring 135 to permit access to the interior of the box 124 to reset the parts. When it is desired that the parts be brought back to the relation illustrated in Fig. 12, the engineer will open the door 133 and by extending the sleeve 155 slidably mounted on the lever 131 a handle is provided by which this lever may be depressed to bring the valve 129 again to its closed position. A leaf spring 156 is secured to the door 136 in such a position that as this door is opened the spring engages with the swinging end of the bar 140 and presses this bar over to a position such that as the valve stem 130 is again brought to the point that the valve is closed against the passage of fluid through the valve casing, this bar is again engaged with the notch 142. At the same time, the swinging end of the bar 140 is brought into contact with the cores 149 and 150 connected with the permanent magnet 147 and is thus held in the engaged position against the tension of the spring 146. A recording meter 157 is secured within the box 124 and the operating rod 158 thereof is engaged by the door 133 as this door is brought to its closed position by the drawing tension exerted by the spring 135 upon the rod 136 connected with the door and in this way the number of times which the door has been opened is enumerated and recorded. As the door 133 is brought to its closed position by the spring 135, the spring latch 138 carried by the lever 131 engages with the catch 137 carried by the door and the parts are then again in the relation disclosed in Fig. 12, the bar 140 being held in engagement in the notch 142 of the stem 130 of the valve by the attraction of the magnet 147 and the spring latch 138 held in its locked relation with respect to the catch 137 by the connection of this valve stem 130 with the lever 131.

The switch 44 is arranged in the wires 24 and a normally inoperative contact located therein has the wire 45 extended to connect with the circuit wires 23, all of these parts and the mechanical structure of the switch being so arranged that when the signal is set at the start and under normal conditions the engagement of the contact brush 20 with the home signal contact in operative relation will cause a current to pass through the wire 24 through the switch 44 and the fluid valve 46 to cause the throttle to be closed and the brakes to be applied. To avoid stopping the locomotive, the engineer may manually operate the switch to shunt the current through the wire 45 to the circuit wire 23 and the resistance 23^a. The circuit through the wire 24 is closed from the point of connection with the switch 44 and the shunting of the current through the wire 45 to the circuit wire 23 causes the alarm 41 to sound and record, at the recorder 42, the polarity of the contact plate with which the contact brush 20 has engaged and the direction of the passage of the current to the locomotive. The switch 44 comprises a case 159, which case is provided with a storage compartment 160 on the lower part thereof, and the doors 161 and 162 are provided for the case 159 and storage compartment 160 respectively to permit access to these parts. A switch bar 168 is provided in the case 159 in alignment with the opening over which the door 161 closes. A double contact 164 is secured in place in the switch box 163 and has the wire 24 connected from the contact brush 20 to a central point thereon so that either of the contacts will pass the current when properly connected with the remainder of the circuits. It is preferable that this contact 164 be made U-shaped so that one of the contacts thereof will be adjacent the rear wall of the switch box 163 and the other contacts will be against the front wall of this box. A contact block 165 is secured on the rear wall above that arm of the contacts 164 which rest against this wall and the lead extent of the wire 24 is connected with this contact 165 and is then passed to connect with the binding plate 154 of the fluid valve 46, and the contact plate 166 connected on the front wall of the switch box 163 has the wire 45 connected therewith and connected at its free end with the locomotive circuit wire 23 in advance of the connection of the resistance 23^a. The switch stem 167 is slidably mounted through the switch box. A circuit connecting blade 168 is mounted on the stem 167 and has the two arms thereof of sufficient extent that when the stem 167 is moved to its extreme position in one direction, one arm of the double switch 164 and the contact plate 165 will be bridged and connected together to form a connection between the extent of the circuit wire 24 leading to this switch 44 and the

extent of the same wire leading therefrom, and a coil spring 169 bears between the front of the switch box 163 and this blade to hold the stem and blade normally in 5 the position above described. The switch handle 170 connected on the outer end of the stem 167 is located at a point where it may be grasped by the engineer when the door 161 is opened and the passage closed 10 thereby is free and unobstructed. By grasping this handle and drawing the stem in a forward direction, the circuit connecting blade 168 is brought to its forward position against the tension of the spring 169 and 15 bridges the forward arm of the double contact 164 and the contact plate 166 thus establishing a circuit connection from the wire 24 connected with the contact brush 20 and the wire 45 which at its free end connects 20 with the circuit wire 23. It will of course be understood that it is desirable that this switch handle be not too readily accessible to the engineer, as to so place the switch that it might be readily operated to cut out the 25 fluid valve 46 and the parts connected with the throttle and the brake setting means would be to encourage the engineer to run past a signal set against him. The shafts 171 and 172 are connected across the case 161, 30 the sprocket wheels 173 and 174 are connected near the ends of the shaft 171 and similar sprockets 175 and 176 are connected in a like manner with the shaft 172, and the sprocket chain 177 is mounted upon the 35 sprocket wheels 173 and 175, a similar sprocket chain 178 being connected over the sprockets 174 and 176. A spring case 179 is mounted around one end of the shaft 172 and a spring 180 is connected with this 40 shaft and with the case in such a manner that a torque is exerted thereagainst in the direction of the arrow in Fig. 7. The cable wheel 181 is secured to the opposite end of the shaft 172, cable 182 is connected at one 45 end with this wheel 181 at a point such that when pulling tension is exerted upon the cable the shaft 172 is revolved against the tension of the spring 180 in a direction opposite to that indicated by the arrow, and 50 this cable is wound over the idler pulleys 183, 184, and 185 from which latter pulley the end is extended and is connected with the door 161 at a point a sufficient distance from the hinge connection thereof that when 55 this door is opened the shaft 172 is given approximately three-fourths of a turn against the tension of the spring 180.

A plurality of glass plates 186 of a size slightly larger than the extent of the opening 187 in the case 159 are placed in the storage receptacle 160 and the case around this opening 187 is recessed as at 188 to receive one of the plates 186 at such a point that it will close access to the interior of 60 the case but yet leave the switch handle 170

in plain view. A suitable locking seal 189 is provided to hold the door 162 of the receptacle 160 in a closed position, a plate 190 is positioned directly within this door 162 and has the rods 191 carried thereby to extend into the body of the receptacle. A pressure plate 192 is mounted behind the glass plate 186 to slide on these rods 191 and the coil springs 193 are provided around the rods between the plates 192 and 190 to 70 hold the pressure plate normally in engagement with the glass plates 186, also to move these plates to the relation indicated in Fig. 7 where they rest against the body portion of the sprocket chains 177 and 178. The 75 shafts 171 and 172, and the sprocket chains 177 and 178 are so positioned that the space between the forward extent of the body portion of these chains and the forward inner face of the case 159 is of sufficient extent 80 that one of the plates 186 may pass therethrough without binding, and the recess portion 188 is so located that as one of the 85 glass plates 186 is passed in an upward direction between the chains and the forward 90 face of the case 159 this glass will be received in the recess portion and will form a transparent closure for the opening 187. The brackets 194 are formed to extend from the inner face of the outer wall of the case 95 159 in alignment with the bottom of the storage receptacle 160 and the spring-held pressure plates 192 hold the several glass plates 186 moved to a position such that one of the plates is entirely without the receptacle and is resting upon these brackets. The sprocket chains 177 and 178 have the 100 brackets 195 carried thereby in the same horizontal plane to be engaged under the lower edge of the glass plate 186 which closes 105 access through the openings 187 and hold this plate securely in the recess 188 provided therefor.

When the engineer finds it desirable to operate the parts, contrary to a closed signal, 110 so that the throttle and brake will not be actuated, the door 161 is opened and the glass 186 obstructing the opening 187 is broken, the fragments of this glass falling down through the open bottom of the case 115 159, and the engineer can then grasp the handle 170 of the switch and by drawing the stem 167 in a forward direction against the tension of the spring 169 the circuit-connecting blade 168 is brought to a position to bridge between one arm of the double contact 164 and the contact plate 166 which establishes communication from the locomotive circuit wire 124 through the wire 45 to the circuit wire 23 to cause the parts connected in this circuit wire to become operative, and at the same time the circuit through that extent of the circuit wire 24 beyond the switch 44 is cut off.

The opening of the door 161 through the 130

connection of the cables 182 with this door and with the wheel 181 secured on the shaft 172 causes the shaft to be turned against the tension of the spring 180 and carries the sprocket chains 177 and 178 around the sprocket wheels 175 and 176 to a point such that brackets 195 thereof are beneath the lower edge of the glass plate 186 supported on the brackets 194. Immediately the door 161 is released, the spring 180 acting through the cable 182 brings this door to a closed position and the turning movement of the shaft 172 under the tension of the spring 180 causes the sprocket wheels 175 and 176 to be revolved in the direction of the arrow and by moving the sprocket chains 177 and 178 raises the plate 186 engaged by the bracket 195 of these chains to a position within the recess 188 to close the openings 187 through which access is had to the switch handle 170.

It is desirable that some means be provided to indicate the number of plates which have been taken from the storage receptacle 160 and to accomplish this object a flexible tape 196 is secured to the pressure plate 192 to extend through an opening provided in the plate 190 and lie between this plate and the door 162. This flexible tape 196 has a plurality of numbers spaced the proper distance apart so that when one of the glass plates 186 is removed from the receptacle 160 the tape will be moved the extent of one number and an opening 197 is provided through the door 162 at a position that the indicating number of the tape will be visible.

The handle 55^a of the brake valve 55 is, as above set forth, so connected through the cable 56, the yoke 198 and the draw rod 199 with the rod 120 connected with the piston rod of the brake-operating cylinder 54 that as fluid is supplied through the pipe 53 to this cylinder 54, the piston 117 will be moved to extend the piston rod 119 therefrom against the tension of the spring 118 and a moving force is transmitted to the brake valve handle 55^a which is brought to the emergency position to accomplish a quick setting of the brake. While it is desirable that the train line pressure be reduced almost simultaneously with the operation of the brake valve 55, it will be understood that the reduction of pressure must not become excessive, as an excessive reduction of pressure will cause the brakes to be set hard and fast against the wheels and so sudden a setting of the brakes may prove disastrous; rather it is desirable that a lower reduction be attained immediately in the train line and that this reduction be maintained constantly to keep the brakes in their bearing relation against the wheels and cause the train to come to a gradual though comparatively short stop. It is to this end that I provide the brake valve con-

trol box and the mechanism contained therein.

The brake-valve control box 122 comprises the case 200 which is adapted to be secured in the locomotive at a point adjacent the 70 brake valve 55, and the parts located therein are constructed to be automatically brought into operation upon the actuation of the piston 117 to move the brake valve handle 55^a from the emergency position to 75 a position that the pressure therein will be maintained constant and neither increase nor permitted to decrease.

The case 200 has a cylinder 201 formed as a part thereof and a pipe 202 connects this cylinder at its outer end with the cylinder brake pipe line or with the locomotive cylinder brake pipe, (line and pipe are not illustrated in the drawings nor herein described as their positioning and arrangement do not form a material part of this invention,) in such relation that upon each operation of the brake valve handle 55^a to 80 permit the supply of air to the cylinder brake line, air is supplied through pipe 202 to the cylinder 201. A shaft 203 is rotatably mounted in suitable bearings in the case 200 and has a gear 204 secured thereon. A piston 205 is mounted to reciprocate in the cylinder 201 and a coil spring 206 received 85 around the piston rod 207 holds this piston normally in the position shown in Fig. 21 where the piston occupies that end of the cylinder 201 adjacent the connection of the pipe 202 therewith. The piston rod 207 extends up through the case into proximity with the gear 204 and this proximate portion of the piston rod 207 has a rack 208 formed thereon to mesh with the teeth of the gear 204, the parts being so arranged 90 that as air is supplied through the pipe 202 to the cylinder 201 a pressure is exerted against the piston 205 to cause this piston to be raised in the cylinder against tension of the spring 206 and this raising of the 95 piston extends an extension of the piston rod in an upward direction to transmit a movement to the gear wheel 204 and consequently rotate the shaft 203, an extension hood 209 being provided on the case 200 100 in line with the piston rod 207 to permit this upward movement of the rack 208. A groove friction roll 210 is rotatably mounted in the case 200 to engage with and bear 105 against the reverse side of the rack 208, the 110 adjusting screw 211 being provided to regulate the bearing pressure of this roll 210 against the rack 208 to thus make it possible to maintain the rack always in the same 115 relation with respect to the gear 204 and to 120 permit adjustment to take up wear.

A spring stem 212 is journaled at its one end in a bearing formed in the case and at its opposite end this stem 212 is revolvably mounted in a bearing 213 formed on the 125

inner end of the shaft 203 so that the shaft and drum may be turned independently of each other and yet have their axes of rotation in alinement. The several springs 214 are received around this spring stem 212, these springs being so mounted that as the drum 212 is turned within its bearing in one direction the springs will have their coils more tightly wound and energy will be stored therein to turn the drum 212 in the opposite direction. The shaft 203 has a hollow sleeve 215 loosely mounted on the inner end thereof and a coil spring 216, the tension of which is adjusted by the adjusting nut 217, received around the shaft holds this sleeve in frictional contact with a shoulder 218 provided on the inner end of the shaft 203 around the bearing 213 formed therein. A ratchet wheel 219 is secured on the spring stem 212 and a dog 220 is carried by the sleeve 215 to engage with the teeth of this ratchet wheel 219 and to prevent turning movement of the sleeve with respect to the ratchet wheel 219 in one direction. Motion is transmitted to turn the shaft 203 as hereinbefore set forth. This turning movement is transmitted to the sleeve 215 by the frictional engagement of this sleeve with the shoulder 218 of the shaft and the engagement of the dog 220 with the teeth of the ratchet wheel 219 causes the spring stem 212 to be turned, thus tightening the coils of the several springs 214, and back movement of the drum 212 is prevented by a dog 221 held by the spring 222 in engagement with a ratchet wheel 223 secured on the spring stem 212. It is desirable that the springs 214 be wound only to a certain tension as excessive winding will strain these springs, and to provide against too great turning movement of the spring stem 212 in a direction to tighten the coils of these springs, I have provided on the stem 212 a gear 224 which meshes with an idler gear 225 mounted on the structure of the case. The gear 224 has a stop 226 thereon and the gear 225 has a similar stop 227, these stops being positioned on the two wheels in such relation that when they come into alinement between the axes of rotation of the two gears, further rotation of the gears will be stopped. By providing the gear 225 with a number of teeth equal to the number of turns which is desired shall be permitted to the spring stem 212 and making the gear 224 of a slightly larger diameter and providing this gear with one additional tooth, the parts can be so arranged that when the desired number of turns has been transmitted to the spring stem 212 by the turning movement of the sleeve 215 frictionally held to revolve with the shaft 203, the stops 227 and 226 will engage one with the other and further rotation will not be permitted, thus causing the sleeve 215 to slide upon the

shoulder 218 as further turning motion is transmitted to the shaft 203.

An idler shaft 228 is revolvably mounted in suitable bearings provided in the case 200 and has its axis of rotation parallel to the axis of rotation of the spring drum 214. A gear 229 mounted on the shaft 228 meshes with a gear 230 carried by the spring drum 214 and a small gear 231 also secured on the shaft 228 meshes with a gear 232 secured on the operating shaft 233. Thus the speed of rotation of the shaft 233 is considerably slower than the speed of rotation of the spring drum 214 from which the shaft 233 derives its energy through the intergearing as described. The speed of rotation of the spring drum 214 is controlled by a fan governor 234 which is mounted on a shaft 235. An idler shaft 236 is mounted in the case 200 and a gear 237 secured thereon meshes with the gear 230 on the spring drum 214, a gear 238 being provided on this shaft 236 to mesh with a gear 239 carried by the governor shaft 235. It will be understood that as it is desired to have the spring drum 214 travel at a higher or lower speed the paddles of the fan governor 234 will be decreased or increased in size and the contact of these paddles with the air will regulate and maintain the speed of rotation of the spring drum 214 at that desired.

The stirrup 198 with which the cable 56 from the brake-operating cylinder 54 is connected has a pivotal connection with an arm 240 which arm is in turn pivoted to the case 200 by a pin 241, and an arm 242 also mounted to have a swinging movement on the pin 240 has the draw rod 199 pivotally connected therewith and extended to connect with the brake-valve handle 55^a, a spring-held catch 243 being provided on the arm 242 to normally engage with the arm 240 and hold these two arms to swing together around the pin 241. The shaft 233 has a sleeve 244 secured thereon and this sleeve has a stop 245 positioned to engage with the stop 246 provided on the arm 247 made in the form of a bell-crank lever and pivoted at its angle at 248 in the case 200. An arm 249 of this lever is extended through an opening provided in the side of the case 200 to project into the path of the arm 240 as it swings around its pivot on the pin 241, and at the opposite end of the lever 247 a coil spring 250 is provided to hold this lever normally in a position that the stop 246 thereof is in a relation to be engaged by the stop 245 as the shaft 233 is rotated.

As tension is exerted upon the cable 56, through the supply of air through pipe 53 to the cylinder 54 and the consequent movement of the piston 117 therein which in turn actuates the rod 120, the connection of this cable with the stirrup 198 causes the two arms 240 and 242 to be moved around their

pivotal connection with the case on the pin 241, the connection of the rod 199 with the brake-valve handle 55^a tending to cause this brake valve to be brought to a position that 5 air is supplied to operate the brakes to stop the train, but as hereinbefore stated, this applying of the brakes must not be too sudden and too positive. By this I mean that the brakes must not be brought positively 10 against the wheels and locked thereon as such an action would cause a breaking of the parts of the mechanism or a wrecking of the train, but rather, it is desirable that sufficient air be admitted to the locomotive- 15 brake line or to the train line as the case may be to cause the brake shoes to be brought into engagement with the wheels and to exert a considerable frictional bearing thereagainst. Then when this pressure has been 20 increased to the proper point, it is desirable that further air supply be cut off and only sufficient air be permitted to pass to the brakes to hold the brakes at the proper tension. A lug 251 is connected on the case 25 200 in the swinging path of the arms 240 and 242 in such relation that when these arms have been swung a sufficient distance by the drawing tension on the cable 56 that the brake-operating handle 55^a has been 30 moved to the proper point to operate the brakes, the catch 243 engages with this lug and is moved against the spring tension to release the arm 240 from its connection with the arm 242 and thus the arm 240 has independent swinging movement around the pin 241. The continued movement of the arm 240 causes this arm to come into engagement with the arm 249 of the bell-crank lever 240 and swing this lever around its pivot at 248 40 to a position such that the stop 246 thereon is moved from its position of engagement with the stop 245 carried by the sleeve 244 secured on the operating shaft 233 and this shaft is permitted to rotate to operate the 45 resetting means.

The shaft 233 has a crank arm 252 secured thereon to be carried around in a path adjacent the end plate 253 of the case 200 and this arm has a slot 254 formed to extend 50 from the outer end thereof. The plate 253 has a cam groove 255, the contour of which is shown in dotted lines in Fig. 20, formed on the inner face thereof adjacent the path of rotation of the arm 252. A resetting lever 256 has the friction roll 257 connected with the one side thereof to be received in the slot 254 formed in the crank arm 252 and on the opposite face of this resetting lever the two friction rolls 258 55 and 259 are mounted to be received in the cam slots 255 formed in the plate 253, all of the parts being so arranged as better shown in Fig. 20 that as the shaft 233 is permitted to be rotated by the stored-up

energy in the springs 214, the resetting lever 56 will be moved from the position indicated in dotted line in Fig. 20 through the slots 260 to engage with the arm 242 and return this arm from the position to which it was swung by the drawing tension on the cable 56 to a position at which the brake-setting air supply is cut off and the engineer's brake valve 55 is brought to a relation that the pressure at the brakes will be maintained. When the air pressure in the cylinder 54 has been sufficiently released that the piston 117 is moved back to the position indicated in Fig. 18 by the tension of the springs 118 bearing thereagainst, the cable 56 is slack and the spring 261 carried by the arm 240 bearing against the arm 242 through the pin 262 causes this arm to be again returned to the position shown in Fig. 19 where it is held to move with the arm 242 by the catch 243. Under some operating 25 conditions, it may be desirable, when the arm 242 is moved to a position to bring the brake-operating handle 55^a to the relation at which air is supplied to the brakes to attain the stopping pressure, to permit slight 30 manual movement or easing off as it were of the brake-operating handle 55^a to cause a more gradual setting of the brakes, and this object is accomplished by providing the cylinder 263 connected with one portion of the draw rods 199 and having the opposite portion thereof slidably received therein and provided with a head 264, the springs 265 and 266 being provided upon opposite sides of this head 264 to hold this head resiliently 35 centered therein. Also if desired, an adjusting screw 267 may be provided through the arm 242 to limit the movement of the arm 240 with respect thereto. Each manual setting of the brakes will cause the supply 40 of air through the pipe 202 to the cylinder 201 and a turning movement will be transmitted to the sleeve 215 to cause the spring 212 to be turned to increase the tension of the several springs 214 and as fluid is 45 supplied to the brake line and consequently to this pipe 202 on each occasion that tension is exerted upon the cable 56 to cause the parts to be moved to the relation to permit turning of the operating shaft 233 and 50 consequent unwinding of the springs 214, the piston 205 will be moved and will cause a turning of the spring drum 212 a sufficient distance to compensate for the releasing of the tension of the spring 214 by the movement of the lever 247 to a position to release the operating shaft 233.

As the mechanism of my invention is to be applied to operate the engineer's brake valve, the structure can be connected for use 55 in conjunction with an automatic brake system or a straight air brake system the difference in the application of the parts

amounting only to mechanical refinements to adapt the structure to accomplish a proper manipulation of the engineer's valve. The operation of the several parts of the structure has been described in detail in connection with the structure thereof; however, a brief recapitulation of the relative operation of the several mechanisms in connection with the setting of the semaphores to change the polarity of the several track contacts 1, 2, 3, and 4 may serve to make this specification somewhat more comprehensive. In the disclosure in Figs. 1 and 2, a single track system in which the train will travel in both directions over the same rails and the signals are positioned to accommodate traffic in either direction is shown, the distant contact 1, and the home contact 3 together with the semaphore 267 connected therewith are arranged to operate for a train traveling toward the right hand, and distant contact 4, home contact 2, and the semaphore 268 are arranged for operation when the train is traveling in the opposite direction. The two track semaphores 267 and 268 are so arranged that when the signal arms thereof are swung to the down or proceed positions, a connection is formed through the circuit wires thereof to bring the batteries into such relation that both the distant signal contact and the home signal contact are of a negative polarity and the positive pole of the battery is grounded thus making the rails of the track also positive as these rails are grounded. When the signal arms of the semaphores are swung to the position as indicated with the semaphore 268 to set the stop signal to be visible to the engineer, the battery connection is made such as indicated for the contacts 2 and 4 that both the distant signal contact and the home signal contact are of positive polarity and by reason of the grounding of the batteries connected in the circuit and the rail of the track, these rails would then present a negative polarity. The permanent magnet and the electromagnetic coils connected therewith are so arranged in the automatic alarm box 41 and the fluid valve for the throttle shift at 46 that as the current passes from the rails through the mass of the engine and then out through the brushes to the track contact, the attracting force of the permanent magnet is only increased and the parts retained thereby are held more securely. Thus when the track semaphores are set at the proceed signal, the only effect of the current when either the brush 19 or the brush 20 comes into bearing relation against one of the track contacts, is to cause the recorder 42 to be operated to make a record that a negative contact has been passed; however, when the semaphore is set at the stop position and the track contacts are thus energized to be of positive

polarity, the bearing of the brush 19 with one of the distant signal contacts will cause the current to flow from this brush through circuit wire 23, resistance 23^a, and the coils of the automatic alarm box 41 to reverse the polarity normally maintained by the permanent magnet therewith and to cause the alarm to be sounded. At the same time, the circuit passing through the recorder 42 makes a record that a track contact set to be positive has been passed. The passage of the brush 20 over one of the home signal contacts with the semaphore thereof set at the stop position will cause the current to flow through this brush, through the circuit wire 24, through switch 44, thence around the coils connected with the permanent magnet in the fluid-valve operating box 46 to neutralize the polarity of this permanent magnet and permits movement of the valve to open the passage from the pipe 49 connected with the air reservoir to the pipe 50 connected with the automatic-throttle shift mechanism 47. From the coils in the box 46 the current is conducted through the wire 24 to the circuit wire 23 to connect therewith at a point beyond the resistance 23^a and the current passing through this wire 23 will cause the alarm to be sounded and the recorder 42 to be operated to record the fact that a positive contact has been passed. The switch 44 is provided in the locomotive circuit wire 24 to permit the engineer to operate the parts so that even though the semaphore may be set against the passage of the train and the home signal contact engaged by the brush 20 is of positive polarity, the circuit through the fluid-valve actuating means can be cut off and the operation of these parts to stop the train avoided, but the operation of the switch 44 by the engineer brings the parts thereof into such relation that a circuit is established from the wire 24 through this switch, through the wire 45 and through the locomotive circuit wire 23 to the automatic alarm 41 to cause this alarm to sound and then through the recorder 42, where a permanent record is made that the positive contact has been passed, and then through the mass of the locomotive to the rails to complete the circuit. The operation and the resetting of the several parts of the structure has been described in detail in connection with the description of the parts thereof and will not therefore here be repeated. The disclosure in Fig. 29 illustrates the parts positioned in a somewhat different relation from the arrangement of the mechanism as shown in Fig. 5. In this disclosure, the distant signal contact brush carried by the locomotive has the locomotive circuit wire 23 connected therewith and the brush 20 has the locomotive circuit wire 24

extending therefrom, these brushes being arranged as hereinbefore described. An electric switch 270 is connected in the locomotive circuit wire 23, a similar switch 271 is connected in the circuit wire 24 and these two switches are in structure and operation identical with the switch 44, the operating mechanism of which is better disclosed in Figs. 6 and 7. The circuit wire 23 is carried from the switch 270 to connect with the electro-magnetic coils in the automatic alarm box 272, which box is identical with the box 41 with the exception that the alarm is connected therewith in a slightly different relation and the fluid permitted to be supplied through the pipe 49 from the air reservoir is used to operate the engineer's throttle 52 in addition to sounding the alarm. A fluid-valve operating box 273 has the locomotive circuit wire 24 extended from the switch 271 to connect with the electro-magnetic coils arranged therein, this box being of the same structure and design as the box 46 disclosed in Fig. 5. The circuit wire 23 leads from the alarm box 272 to connect with the recorder 42 and the circuit is then grounded upon the mass of the engine by the wire 43 as disclosed in Fig. 5. The third wire or the shunt wire 274 connected with the switch 270 is extended to join with the circuit wire 23 at a point beyond the connection of the alarm box 272 therein and a shunt wire 275 is connected from the third contact in the switch 271 and joined with the circuit wire 23 also at a point beyond the alarm box 272; further the circuit wire 24 after leaving the fluid-valve operating box 273 is connected with the same extent of the circuit wire 23 and in this way it will be seen that regardless of which of the brushes 19 or 20 strikes the track contacts and regardless of which course the circuit may traverse, the circuit is always completed through that part of the locomotive circuit wire 23 which is connected with the recorder 42 and a record will be made of the condition of each track contact which may be passed and engaged by either the brush 19 or the brush 20.

Two cylinders 276 and 277 in structure and operation similar to the throttle-shift mechanism 47 are connected together and have the yokes 278 thereof also connected together and to both of the piston rods in such relation that when fluid is supplied to the cylinder from the box 272 through the pipe 279 or to the cylinder 277 from valve-operating box 273 through the pipes 280, a drawing tension will be exerted upon the cable 51 to bring the throttle or control to a position where the power is shut off. The pipe 281 is connected with the cylinder 276 at a point passed by the piston of this cylinder at its free inward thrust so that when the piston has been moved a sufficient

distance by the supply of air through the pipe 279 air will be permitted to flow through this pipe 281 to operate the alarm 282 connected therewith. The pipe 280 extends in connection with the cylinder 277 at the one end thereof at a point corresponding to the connection of the pipe 50 in the disclosure in Fig. 5 and this cylinder has the pipe 53 connected therewith and extended to the brake-operating cylinder 54 which is connected to actuate the parts in a manner identical with the disclosure in Fig. 5.

With the structure as above described, when the brush 19 strikes one of the track contacts set to indicate that the engineer should proceed with care, the circuit will pass through the circuit wire 23, through the switch 270, then to the operating box 272 where communication from the pipe 49 through the pipe 279 to the cylinder 276 is established and from this point the circuit continues on through the wire 23 to the recorder 42 where a permanent record is made, then on through the structure of the engine to the rails and the circuit is then completed through the grounding of these rails and the grounding of the batteries which is in operative connection with the contact struck by the brush 19. The supply of air through the pipe 279 to the cylinder 276 causes the piston therein to be moved against the tension of the spring which normally holds this piston with the rod thereof drawn into the cylinder and causes a drawing tension upon the cable 51 to bring the throttle 52 or other power-controlling means to a position to shut off power; then when this piston in the cylinder 276 has been moved a sufficient distance communication is established to the pipe 281 and the air passing therethrough causes the alarm 282 to be sounded. If for certain traffic conditions it is found desirable to preclude the operation of the throttle 52 to shut off the power when the track contacts are set as above described, the engineer then operates the switch 270 to shunt the current through the wire 274 and thus avoid passage of this current through the box 272. With this connection of the circuit communication is not established from the pipe 49 through the pipe 279 to the cylinder 276 but these parts remain in their inoperative relation and the only effect of the current passing through the circuit wire 23 is to operate the recorder 42 to furnish its permanent record of the condition of the contacts passed. When the brush 20 strikes a home signal contact set at stop, the current will pass through the wire 24, through the switch 271, thence to the coils of the fluid-valve operating box 273 to release the valve mounted therein and to permit the passage of fluid from the pipe 49 through the pipe 280 to the cylinder 277. This supply of fluid

to the cylinder 277 causes the piston contained therein to be moved against the tension of the spring which normally holds the piston with its piston rod drawn into the cylinder and a tension is exerted against the cable 51 to cause the throttle to be brought to a position to cut off the power; also when the piston has been moved a sufficient distance by the pressure of the air from the pipe 280, communication is established through the pipe 53 to supply air to the brake-operating cylinder 54 and the parts of this cylinder will be actuated to move the brake-operating handle 55^a of the brake valve 55 to a position to supply air to the brakes; then when the mechanism in the brake-valve control box has been brought into operation by the energy stored in the springs contained therein the draw rod 199 will be actuated to return the brake-valve handle 55^a to a position that the proper pressure to hold the brakes will be maintained. The manual operation of the switch 271 to shunt the current from the circuit wires 24 connected with the brush 20 through the wire 275 to the circuit wire 23 will cut out that part of the circuit wire connected with the valve-operating box 273 and the only effect of the passage of the current will be to record in the recorder the condition of the contact which has been passed by the brush 20. With the use of this arrangement of the parts, it will be seen that when the brush 19 strikes a distant signal contact set to indicate to the engineer that the train should proceed with care, the judgment of the engineer in determining what degree of care to be used is not to be relied upon but the parts are operated to bring the throttle to a position that the power is cut off and the train will then stop through its own loss of momentum or will drift or run idle from the inertia gathered from the movement under power until a home signal contact set against the train is engaged by the brush 20 and this completes the circuit through the wire 24 to cause an operation of the means contained in the fluid-valve control box 273 to permit passage of fluid from the pipe 49 through the pipe 280 and the parts connected therewith to eventually reach the brake-operating cylinder 54 and moves the brake-operating handle 55^a to a position that the brakes will be set. Other advantages of this arrangement of the parts will be readily recognized and will not therefore be here discoursed upon at length.

From the foregoing it will be seen that I have provided a train stop and adviser so constructed and arranged on the locomotive that the parts coöperating with one another are automatic, positive and efficient in operation and are so connected that even though the automatic sequence of operation may be disturbed by a manual actuation of the parts

by the engineer, a permanent record of the condition of the signals will be furnished.

While I have herein shown and described specific mechanisms to accomplish the various operations and specific arrangement of these mechanisms, it will be understood that slight changes might be made in the form and arrangement of the parts without departing from the spirit and scope of my invention, and hence I do not wish to be limited thereto except for such limitations as the claims may import.

I claim:—

1. An automatic stop and adviser for locomotives comprising brake setting means and drive power control means arranged to be consecutively operated by common actuating means, an electric circuit for the locomotive arranged to be energized from a track circuit, means connected in said circuit to be actuated by energization of the circuit to act as common actuating means for the brake setting means and drive power control means, means to record energization of the locomotive circuit, manually operable means to be operated to restore said common actuating means to normal, a case within which the manually operable means is inclosed provided with a door to be opened in obtaining access to the manually actuatable means, and means to register the opening of said door.

2. An automatic stop and adviser for locomotives comprising brake setting means and drive power control means constructed to be consecutively operated by common actuating means and arranged in a relation that the setting of the brake is made subsequent to the cutting off of the power, means to operate the common actuating means, manually actuatable means to restore the common operating means to reset the two means controlled thereby, a case inclosing said manually actuatable means and provided with a door closing the opening through which access is had to the manually actuatable means which door is arranged to be normally held closed, and mechanically operated means to register the opening of the door.

3. An automatic stop and adviser for locomotives comprising brake-setting means, drive-power control means, an electric circuit for the locomotive, means connected in said circuit to be actuated by the passage of current therethrough in one direction to operate said parts to bring the locomotive to a stop, contact means connected with the locomotive circuit, track contacts located at suitable points to be engaged by the locomotive contacts, a track circuit connected with said contacts and arranged to have the current passed therethrough in either direction to reverse the polarity of the track contacts, means connected in the locomotive

115

120

125

130

circuit to make a permanent visible record of the polarity of the track contacts as engaged by the locomotive contacts, and means connected in the locomotive circuits to be 5 manually moved by the engineer to cut out that part of the circuit in which the means to operate the brake-setting means and the drive-power control is connected.

4. An automatic stop and adviser for locomotives comprising brake-setting means, drive-power control means, an electric circuit for the locomotive, means connected in said circuit to be actuated by the passage of current therethrough in one direction to operate said parts to bring the locomotive to a stop, contact means connected with the locomotive circuit, track contacts located at suitable points to be engaged by the locomotive contacts, a track circuit connected with 10 said contacts and arranged to have the current passed therethrough in either direction to reverse the polarity of the track contacts, means connected in the locomotive circuit to make a permanent visible record of the 15 polarity of the track contacts as engaged by the locomotive contacts, means connected in the locomotive circuit to be manually moved by the engineer to cut out that part of the circuit in which the means to operate the 20 brake-setting means and the drive-power control is connected, and means connected with said manually moved means to make a visible record of the operation thereof.

5. An automatic stop and adviser for locomotives comprising brake-setting means, drive-power control means, actuating means for said parts capable of movement to cut off the power and subsequently apply the 25 brakes, a circuit wire for the locomotive provided with two branches, a contact connected with each of said branches, contact plates connected along the track to be engaged by said contacts, track circuits so connected with said contact plates that the engagement 30 of the locomotive contacts therewith completes the circuit through the locomotive circuit wires, means connected in one of said branches to be brought into operation by the completion of the circuit through this 35 branch and passage of current therethrough to operate the actuating means to cut off the power and apply the brakes, means located in the other branch to be energized by the passage of current therethrough to cause the 40 actuating means to be operated to cut off the power and permit the locomotive to drift, and means to be manually moved by the engineer connected in each of said branches and having an electrical connection with 45 said first means connected therein to cut this first means entirely out of the circuit.

6. An automatic stop and adviser for locomotives comprising brake-setting means, drive-power control means, actuating means for said parts capable of movement to cut off the power and subsequently apply the 50 brakes, a circuit wire for the locomotive provided with two branches, a contact connected with each of said branches, contact plates 55

connected along the track to be engaged by said contacts, track circuits so connected with said contact plates that the engagement of the locomotive contacts therewith completes the circuit through the locomotive circuit wires, means connected in one of said branches to be brought into operation by the completion of the circuit through this branch and passage of current therethrough to operate the actuating means to 70 cut off the power and apply the brakes, means located in the other branch to be energized by the passage of current therethrough to cause the actuating means to be operated to cut off the power and permit the locomotive to drift, and means connected in the locomotive circuit wire to record the passage of current through either of the branches thereof.

7. An automatic stop and adviser for locomotives comprising brake-setting means, drive-power control means, actuating means for said parts capable of movement to cut off the power and subsequently apply the brakes, a circuit wire for the locomotive provided with two branches, a contact connected with each of said branches, contact plates connected along the track to be engaged by said contacts, track circuits so connected with said contact plates that the engagement of the locomotive contacts therewith completes the circuit through the locomotive circuit wires, means connected in one of said branches to be brought into operation by the completion of the circuit through this 90 branch and passage of current therethrough to operate the actuating means to cut off the power and apply the brakes, means located in the other branch to be energized by the passage of current therethrough to cause the actuating means to be operated to cut off the power and permit the locomotive to drift, and means to be manually moved by the engineer connected in each of said branches and having an electrical connection with 95 said first means connected therein to cut this first means entirely out of the circuit.

8. An automatic stop and adviser for locomotives comprising brake-setting means, drive-power control means, actuating means for said parts capable of movement to cut off the power and subsequently apply the brakes, a circuit wire for the locomotive provided with two branches, a contact connected with each of said branches, contact plates connected along the track to be engaged by said contacts, track circuits so connected with said contact plates that the engagement of the locomotive contacts therewith completes the circuit through the locomotive circuit wires, means connected in one of said branches to be brought into operation by the completion of the circuit through this branch and passage of current therethrough to operate the actuating means to cut off the 115 power and apply the brakes, means located in the other branch to be energized by the passage of current therethrough to cause the actuating means to be operated to cut off the power and permit the locomotive to drift, and means to be manually moved by the engineer connected in each of said branches and having an electrical connection with 120 said first means connected therein to cut this first means entirely out of the circuit.

125

- power and apply the brakes, means located in the other branch to be energized by the passage of current therethrough to cause the actuating means to be operated to cut off 5 the power and permit the locomotive to drift, and an alarm so connected with the actuating means that as the power is cut off this alarm is sounded to enunciate the fact to the engineer.
- 10 9. An automatic stop and adviser for locomotives comprising brake-setting means, drive-power control means, actuating means for said parts capable of movement to cut off the power and subsequently apply the 15 brakes, a circuit wire for the locomotive provided with two branches, a contact connected with each of said branches, contact plates connected along the track to be engaged by said contacts, track circuits so connected 20 with said contact plates that the engagement of the locomotive contacts therewith completes the circuit through the locomotive circuit wires, means connected in one of said branches to be brought into operation by the 25 completion of the circuit through this branch and passage of current therethrough to operate the actuating means to cut off the power and apply the brakes, means located in the other branch to be energized by the 30 passage of current therethrough to cause the actuating means to be operated to cut off the power and permit the locomotive to drift, means to be manually moved by the engineer connected in each of said branches and having 35 an electrical connection with said first means connected herein to cut this first means entirely out of the circuit, switches mounted in each of the branches of said locomotive circuits to be manually moved by the 40 engineer to a position that the actuating means connected therein is entirely cut from the circuit, and recording means connected to said switches so that the recording means will be operative when either of the branches 45 of the locomotive circuit is energized.
10. An automatic stop and adviser for locomotives comprising brake-setting means, drive-power control means, actuating means for said parts capable of movement to cut off the power and subsequently apply the 50 brakes, a circuit wire for the locomotive provided with two branches, a contact connected with each of said branches, contact plates connected along the track to be engaged by 55 said contacts, track circuits so connected with said contact plates that the engagement of the locomotive contacts therewith completes the circuit through the locomotive circuit wires, means connected in one of said 60 branches to be brought into operation by the completion of the circuit through this branch and passage of current therethrough to operate the actuating means to cut off the power and apply the brakes, means located 65 in the other branch to be energized by the
- passage of current therethrough to cause the actuating means to be operated to cut off the power and permit the locomotive to drift, means to be manually moved by the engineer connected in each of said branches and having 70 an electrical connection with said first means connected herein to cut this first means entirely out of the circuit, switches mounted in each of the branches of said locomotive circuit to be manually moved by the 75 engineer to a position that the actuating means connected therein is entirely cut from the circuit, recording means located in said locomotive circuit, switches so connected that the recording means will be operative when either of the branches of the locomotive circuit is energized, and mechanical means connected with each of said switches to make a permanent visible record of the manual operation thereof.
11. An automatic stop and adviser for locomotives comprising fluid-actuated means connected with the engineer's brake valve to move this valve to a position that the emergency air supply is open to the brake line, 80 and spring-actuated means brought into operation by said actuation of the engineer's brake valve to move this valve to the holding position when the emergency position has been maintained for a sufficient length 85 of time to attain the desired air pressure within the brake line.
12. An automatic stop and adviser for locomotives comprising fluid-actuated means connected with the engineer's brake valve to move this valve to a position that the emergency air supply is open to the brake line, 90 and spring-actuated means brought into operation by said actuation of the engineer's brake valve to move this valve to the holding position when the emergency position has been maintained for a sufficient length 95 of time to attain the desired air pressure within the brake line, and means to be brought into operation upon each movement of the engineer's brake valve to supply air to the brake line to keep the spring at the proper tension to properly operate the parts connected therewith.
13. An automatic stop and adviser for locomotives comprising fluid-actuated means connected with the engineer's brake valve to move this valve to a position that the emergency air supply is open to the brake line, 100 and spring-actuated means brought into operation by said actuation of the engineer's brake valve to move this valve to the holding position when the emergency position has been maintained for a sufficient length 105 of time to attain the desired air pressure within the brake line, and means to be brought into operation upon each movement of the engineer's brake valve to supply air to the brake line to keep the spring at the proper tension to properly operate the parts connected therewith.
14. An automatic stop and adviser for locomotives comprising fluid-actuated means connected with the engineer's brake valve to move this valve to a position that the emergency air supply is open to the brake line, 110 and spring-actuated means brought into operation by said actuation of the engineer's brake valve to move this valve to the holding position when the emergency position has been maintained for a sufficient length 115 of time to attain the desired air pressure within the brake line, and means to be brought into operation upon each movement of the engineer's brake valve to supply air to the brake line to keep the spring at the proper tension to properly operate the parts connected therewith.
15. An automatic stop and adviser for locomotives comprising fluid-actuated means connected with the engineer's brake valve to move this valve to a position that the emergency air supply is open to the brake line, 120 and spring-actuated means brought into operation by said actuation of the engineer's brake valve to move this valve to the holding position when the emergency position has been maintained for a sufficient length 125 of time to attain the desired air pressure within the brake line, and means to be brought into operation upon each movement of the engineer's brake valve to supply air to the brake line to keep the spring at the proper tension to properly operate the parts connected therewith.

nected therewith, and means to prevent overwinding of this spring.

14. An automatic stop and adviser for locomotives comprising in combination 5 with fluid actuated means to operate the engineer's brake valve to set the brakes, a cylinder provided with a piston the rod of which is adapted to be extended as fluid is supplied to the cylinder, a second cylinder 10 and its piston thereof arranged in a like manner, a connection between said piston rods so formed that said pistons are caused to move together, a fluid-supply connected with each of said cylinders at a point in 15 front of the pistons, an alarm, a connection from the one cylinder to the alarm, a connection from the second cylinder to the fluid-actuated brake-setting means, each of 20 said connections so formed that communication is established therewith when the piston is at its extreme outer stroke, and said parts so arranged that the supply of fluid to the one cylinder causes the power to be cut off and the alarm to be sounded and 25 the supply to the second cylinder causes the power to be cut off and the brakes to be set.

15. An automatic stop and adviser for locomotives comprising in combination 30 with fluid actuated means to operate the engineer's brake valve to set the brakes, a cylinder provided with a piston the rod of which is adapted to be extended as fluid is supplied to the cylinder, a second cylinder 35 and its piston thereof arranged in a like manner, a connection between said piston- rods so formed that said pistons are caused to move together, a fluid-supply connected with each of said cylinders at a point in 40 front of the pistons, an alarm, a connection from the one cylinder to the alarm, a connection from the second cylinder to the fluid-actuated brake-setting means, each of 45 said connections so formed that communication is established therewith when the piston is at its extreme outer stroke, said parts so arranged that the supply of fluid to the one cylinder causes the power to be cut off and the alarm to be sounded and the supply 50 to the second cylinder causes the power to be cut off and the brakes to be set, and electrically actuated means to control the supply of fluid to each of said cylinders.

16. An automatic stop and adviser for 55 locomotives comprising in combination with fluid-actuated means to cut off the power and like means to operate the engineer's brake valve to set the brakes, a fluid-supply pipe to said fluid-actuated means, a valve 60 connected in said pipe, an electric circuit for the locomotive, a contact connected with said circuit, a track circuit provided with a track contact to be engaged by said locomotive, contact to energize said locomotive circuit, and said track circuit so ar-

ranged that the current may be passed therethrough in either direction, and means connected in said circuit and connected with the fluid valve in such a manner that the supply of current through said circuit in 70 the one direction tends to hold the valve closed and the supply of current in the opposite direction releases the holding means and permits the valve to open.

17. An automatic stop and adviser for 75 locomotives comprising in combination with fluid-actuated means to cut off the power and like means to operate the engineer's brake valve to set the brakes, a fluid-supply pipe to said fluid-actuated means, a valve 80 connected in said pipe, an electric circuit for the locomotive, a contact connected with said circuit, a track circuit provided with a track contact to be engaged by said locomotive contact to energize said locomotive 85 circuit, said track circuit so arranged that the current may be passed therethrough in either direction, means connected in said circuit and connected with the fluid valve in such a manner that the supply of current 90 through said circuit in the one direction tends to hold the valve closed and the supply of current in the opposite direction releases the holding means and permits the valve to open, said valve and the operating 95 parts constructed to require manual resetting to permit the locomotive to proceed, and means connected therewith to furnish a visible record of the manual resetting.

18. An automatic stop and adviser for 100 locomotives comprising in combination with fluid-actuated means to cut off the power and like means to operate the engineer's brake valve to set the brakes, a fluid-supply pipe to said fluid-actuated means, a valve 105 connected in said pipe, an electric circuit for the locomotive, a contact connected with said circuit, a track circuit provided with a track contact to be engaged by said locomotive contact to energize said locomotive circuit, said track circuit so arranged that the current may be passed therethrough in either direction, means connected in said circuit and connected with the fluid valve in such a manner that the supply of current through 110 said circuit in the one direction tends to hold the valve closed and the supply of current in the opposite direction releases the holding means and permits the valve to open, said valve and the operating parts constructed 115 to require manual resetting to permit the locomotive to proceed, means connected therewith to furnish a visible record of the manual resetting, and means connected in the circuit to be manually moved by the engineer to preclude operation of the electrically-actuated means when the relation of the track and locomotive circuit is such that this means would normally be actuated.

19. An automatic stop and adviser for 120

comotives comprising in combination with fluid-actuated means to cut off the power and like means to operate the engineer's 5 brake valve to set the brakes, a fluid-supply pipe to said fluid-actuated means, a valve connected in said pipe, an electric circuit for the locomotive, a contact connected with said circuit, a track circuit provided with a track contact to be engaged by said locomotive 10 contact to energize said locomotive circuit, said track circuit so arranged that the current may be passed therethrough in either direction, means connected in said circuit and connected with the fluid valve in such a 15 manner that the supply of current through said circuit in the one direction tends to hold the valve closed and the supply of current in the opposite direction releases the holding means and permits the valve to 20 open, said valve and the operating parts constructed to require manual resetting to permit the locomotive to proceed, means connected therewith to furnish a permanent visible record of the manual resetting, an 25 electric switch connected in the locomotive circuit to be operated by the engineer to cut out said electrically-actuated means, and means connected with the switch to furnish a permanent visible record of the manual 30 operation thereof.

20. An automatic stop and adviser for locomotives comprising in combination with brake-setting means and drive-power control means, electrically-actuated means to bring said parts into operation to stop the locomotive, an electric circuit for the locomotive in which said electrically actuated means is connected, a contact connected in 35 said locomotive circuit, a track circuit provided with a contact to be engaged by said locomotive contact to energize the locomotive circuit and cause the electrically-actuated means to become operative, a switch connected in the locomotive circuit to be 40 manually operated to shunt the current from its passage through the electrically actuated means and to prevent the operation of the parts to stop the locomotive, means connected with the switch to be operated by the 45 manipulation thereof to register said operation, and means connected in the locomotive circuit to make a permanent visible record of the passage of the current therethrough.

21. An automatic stop and adviser for locomotives comprising in combination with 50 brake-setting means and drive-power control means, electrically-actuated means to bring said parts into operation to stop the locomotive, an electric circuit for the locomotive in which said electrically-actuated means is connected, a contact connected in said locomotive circuit, a track circuit provided with contacts to be engaged by said locomotive contacts to energize the locomotive 55 circuit and cause the electrically-actuated means to become operative, a switch connected in the locomotive circuit to be operated by the manipulation thereof to register said operation, and means connected in the locomotive circuit to make a permanent visible record of the passage of the current therethrough.

22. An automatic stop and adviser for locomotives comprising in combination with a locomotive having brake operating mechanism mounted thereon, an electric circuit 60 for the locomotive, a track circuit adapted to have the current reversed therein, means connected in said locomotive circuit and said track circuit in such relation that said locomotive circuit is energized from said track circuit, means connected in the circuit of the locomotive to be actuated by the passage of the current therethrough in one direction to bring the brake operating mechanism into operative relation, and an automatic 65 alarm also connected in said circuit to be operative upon the passage of the current therethrough in a direction to actuate the brake operating mechanism and to be inoperative upon the passing of current through 70 said circuit in the opposite direction.

23. An automatic stop and adviser for locomotives comprising in combination with a locomotive having brake operating mechanism mounted thereon, an electric circuit 75 for the locomotive, means connected in the circuit to be actuated by the passage of current therethrough in one direction to cause the brake setting mechanism to be brought into operative relation, a contact carried by 80 the locomotive and connected in said locomotive circuit, a track circuit, track contacts connected in said circuit in such relation that their polarity may be reversed and thus the engagement of the contacts carried 85 by the locomotive therewith will cause the passage of electrical current through the locomotive circuit in a direction to actuate the electrically actuated means to control the operation of the brake setting mechanism 90 when the track contact is set to be of the one polarity and will pass the current through the locomotive circuit in the opposite and inoperative path when the track contact is connected to be of the opposite polarity, an 95 automatic alarm connected in said locomotive circuit to be brought into operation by the passage of current therethrough in a direction to operate said electrically actuated means and said alarm mechanically con- 100

structed to automatically return to an inoperative relation.

24. An automatic stop and adviser for locomotives comprising in combination with 5 a locomotive having brake operating mechanism mounted thereon, electrically actuated means to bring said brake setting mechanism into operation, a suitable circuit for said electrically actuated means, means connected in the circuit to sound an alarm upon the energization of said circuit, a contact carried by said locomotive circuit, a track circuit, a home contact; and a distant contact, connected in the track circuit adapted 10 to be engaged by the contact of the locomotive circuit to cause this circuit to be energized, means connected in the locomotive circuit to record the energization of said circuit, and all of said parts so arranged that 15 the setting of the signal is recorded on the locomotive by the engagement of the contact carried thereby with the contacts in the track circuit.

25. An automatic stop and adviser for 25 locomotives comprising in combination with a locomotive having brake operating mechanism mounted thereon, an electric circuit for the locomotive, means connected in the circuit to be actuated by the passage of the 30 current therethrough in one direction to bring the brake operating mechanism into operative relation, means located along the track in advance of the signal to the engineer to be engaged by parts carried by the 35 locomotive and to energize said locomotive circuit as the locomotive approaches the signal, and a recording means connected in the locomotive circuit to be actuated by the energization thereof to make a permanent visible 40 record of the setting of the signal before the passage of the train.

26. An automatic stop and adviser for locomotives comprising in combination with a locomotive having brake operating mechanism mounted thereon, an electric circuit for 45 the locomotive, means connected in said circuit to be actuated by the passage of the current therethrough in one direction to cause the brake setting mechanism to be brought 50 into operative relation, a contact carried by the locomotive and connected in said locomotive circuit, a track circuit, a signal system connected with said track circuit, contacts connected in the track circuit in such relation 55 that by a shifting of the signal the polarity thereof is reversed and thus the engagement of the contacts carried by the locomotive therewith will cause the passage of the electrical current through the locomotive circuit in opposite directions, said contacts located in advance of said signal and a recording means connected in the locomotive circuit to be operated by the energization 60 of the locomotive circuit through the

engagement of the contacts thereof with the 65 track contacts to make a permanent visible record of the setting of the signal.

27. An automatic stop and adviser for locomotives comprising brake setting means, drive power control means, an electric circuit for the locomotive, means connected in said circuit to be actuated by the passage of current therethrough to operate said parts to bring the locomotive to a stop, contact means connected with the locomotive circuit, a signal system located along the track, track contacts located at suitable points in advance of said signal, track circuits connected with said contacts and with said signal in such a manner that the engagement 80 of the locomotive contacts with one of said track contacts will energize the locomotive circuit, and means connected in the locomotive circuit to make a permanent visible record of the setting of the signal as the 85 train approaches the signal through the engagement of the locomotive contacts with the track contacts.

28. An automatic stop and adviser for locomotives comprising brake setting means, 90 an electric circuit for the locomotive, means connected in said circuit to be actuated by the passage of current therethrough in one direction to operate said parts to bring the locomotive to a stop, contact means connected with the locomotive circuit, a signal system located along the track, track contacts located at suitable points in advance of said signal, track circuits connected with said contacts and said signal so connected 100 in said circuit that upon the shifting thereof the polarity of the track contact is reversed, and means connected in the locomotive circuit to make a permanent visible record of the setting of the signal as the 105 train approaches thereto through the engagement of the locomotive contacts with the track contacts placed in advance of the signal.

29. An automatic stop and adviser for locomotives comprising brake setting means, drive power control means, an electric circuit for the locomotive to have the current passed therethrough, electrically actuated means connected in said circuit to bring the 115 brake setting means and the power control means into operation to stop the train upon the supply of current through the circuit, a contact connected with the one terminal of the locomotive circuit and the opposite 120 terminal grounded upon the body structure of the locomotive, a signal system located along the track, track contacts located at points in advance of said signal, track circuits arranged to include the rails and contacts and to be connected with said signal, and means connected in the locomotive circuit to be actuated upon the engagement of 125

the locomotive contacts with the track contacts in advance of the signal to indicate the setting of said signal.

- 30. An automatic stop and adviser for locomotives comprising brake setting means, drive power control means, an electric circuit for the locomotive range to have the current pass in either direction therethrough, electrically actuated means connected in said circuit to bring the brake setting means and the power control means into operation to stop the train upon the supply of current through the circuit in one direction, a contact connected with one of the terminals of the locomotive circuit and the opposite terminal grounded upon the body portion of the locomotive, a signal system located along the track, track contacts mounted adjacent the rails at a point in advance of the signal, a track circuit arranged to include the rails and said contact and having the signal connected therein in such a manner that the shifting of the signal will cause a reversal of the direction of passage of the current through the track circuit, and means connected in the locomotive circuit to record the direction of travel of the current through said circuit and to consequently indicate the setting of the track signal as the train approaches thereto.

31. An automatic stop and adviser for locomotives comprising in combination with brake setting means and drive power control means, an electric circuit for the locomotive to govern the actuation of said parts, 35 a contact connected in the locomotive circuit, a track signal system, track contacts placed in advance of said signal, a track circuit arranged to include said contacts and the signals so constructed that upon the 40 shifting thereof the polarity of the contacts is reversed, an alarm connected in the locomotive circuit to be operated by the passage of the current therethrough in the direction to actuate said brake setting and drive 45 power control means and to audibly announce to the engineer that the track contact has been engaged, and means connected in the locomotive circuit to make a permanent visible record of the polarity and con- 50 sequent energization of each of the track contacts as passed and to thus indicate and record the setting of the signal as the train approaches the signal.

In testimony whereof I affix my signature 55 in presence of two witnesses.

JOSEPH BATTAGLINO.
